UNITED STATES PATENT OFFICE

161,449

SHOE SOLE

John Hoza, Belcamp, Md.

Application July 21, 1950, Serial No. 11,307

Term of patent 14 years

(Cl. D7—5)

To all whom it may concern:

Be it known that I, John Hoza, a citizen of the United States, residing at Belcamp, in the county of Harford and State of Maryland, have invented a new, original, and ornamental Design for Shoe Soles, of which the following is a specification, reference being had to the accompanying drawing, forming part thereof.

Figure 1 is a plan view of a shoe sole showing my new design.

Figure 2 is a side view.

Figure 3 is a bottom view.

Figure 4 is a sectional view on the line 4—4 of Figure 1.

I claim:

The ornamental design for a shoe sole, as shown.

JOHN HOZA.
